APPARATUS FOR PRODUCING PERSPECTIVE DRAWINGS

Erik G. Hysing, Stockholm, Sweden, assignor to Aktiebolaget Kontrollinstrument, Stockholm, Sweden, a corporation of Sweden

Application March 22, 1949, Serial No. 82,752

7 Claims. (Cl. 33—77)

1

A known type of apparatus for producing perspective drawings contains two rulers, mutually turnably connected, which are each separately slidably arranged in a fixture which is in its turn turnably mounted about a fixed point. In this way there is thus formed a triangle, the sides of which are the two rulers and the connection line between the two fixed points, respectively. In the connection point between the two rulers, finally there is turnably mounted a third ruler which is preferably intended for the vertical position.

The two first mentioned rulers are arranged to be pushed into or pulled out of rollers, provided in immediate vicinity of the fixed points.

In the hitherto known perspective drawing apparatus of the above mentioned kind, one has had no freedom in choosing the perspective. The perspective is determined by two distances, viz. the so called D-distance or D-value and the so called H-distance or H-value. The D-value is the distance from the midpoint of the horizontal line to the vanishing point on the one side of the horizontal line, or in other words, half the perspectively reproduced horizontal line, whereas the H-value is represented by the distance from the observation point to the midpoint of the horizontal line. As a measure of the perspective it is customary to state the tangent of the perspective angle or in other words, the H-value, divided by the D-value. It is now obvious that in a perspective ruler of the above mentioned kind, one can put the H-value in any chosen way and, consequently, obtain any desired value of the perspective angle. Any separate value of the perspective angle, however, will be directly related to a predetermined scale, because the D-value in the hitherto known perspective rulers has been fixed and could not be changed. The advantage of a perspective ruler of the kind here described, however is, that one can place perspectively graded scales along the rulers in the apparatus, but even these scales must obviously be fixed, one for each chosen perspective angle. Therefore, the disadvantage will occur that one cannot by the same perspective drawing apparatus draw a large object and a small object, because the large object may with the present scales be so large that it extends over the frame of the drawing board, and the small object may be so small that it loses too much in clearness, and even perhaps cannot be drawn due to the thickness of the pencil line. For this reason, it is very important in such perspective drawing apparatus which have perspectively graded scales, that the D-value may be changed.

2

Further details of the invention will be apparent from the following description in connection with the attached drawings in which Fig. 1 shows an apparatus for producing perspective drawings according to the invention in total view, and Figs. 2, 3, 4, and 5 show parts of the arrangement according to Fig. 1.

It is assumed that the arrangement according to Fig. 1 is clamped on a drawing board 10, on the back side of which there are according to the invention arrangements for slidably fixing bars 11 and 12, so that they extend exactly in line with each other. The bars are provided, at their outer ends, with a perpendicular pivot or shaft 50, see Fig. 3, on which rollers 13, 14 are mounted. The rollers 13, 14 contain, in a manner known from so called steel tape measures, transversally bent steel tapes or metal tapes 15, 16, which can be rolled up on the rollers and which are turnably secured to a head 17 which is suitably combined with a grip for simplifying the operation of the apparatus. The head 17 also carries a turnable ruler 18, referred to below as a linear ruler. On the steep tapes 15, 16 two further rulers 19, 20 are mounted which are referred to as the perspective rulers.

It is suitable that the linear ruler 18 be provided with an elongation 21, directed downwards and formed as a triangular template, one side of which forms an extension of the ruler 18, another side of the triangle being perpendicular thereto and the third side of the triangle being disposed at a predetermined angle, the so called perspective angle. In such apparatus for producing perspective drawings which are intended for use with different perspective angles, the triangular template 21 should preferably be interchangeable, which may, for instance, be effected by loosening the grip 17, changing the template for another one and tightening again the grip in place.

In connection with the change of the triangular member, as a rule, the scales of the perspective rulers 19, 20 must also be changed. In order that this shall be possible, the scales are put in place by inserting their ends under a pair of hook forming means 22, 23, and 24, 25, respectively. The scale of the ruler 18 is linearly marked, whereas the scales 19 and 20 are mutually equal although inverted. They may be calculated or they may be constructed in such a way that they give direct perspective length measure in the chosen perspective, represented by the scales 19 and 20 as well as by the triangular member 21.

The perspective rulers 19 and 20 together with the rulers 15, 16 are normally freely rotatable

in relation to the grip 17 and in the same way the rulers may normally be freely elongated or shortened by pulling out a chosen length of the steel tape from the rollers 13, 14 or by pushing it into the rollers. For certain purposes, however, it is desirable to lock the tapes in adjusted position and for this purpose, a locking member 26 is provided in order to prevent the ruler 15 from turning with respect to the grip 17, and a similar locking member 27 is provided to prevent the ruler 16 from turning with respect to the grip 17. Finally, a locking screw 28 is provided to prevent the ruler 16 from elongating or shortening of the ruler 16 by pulling steel tape out from the roller 14 or by pushing it into the roller. If desirable a similar locking screw could be arranged in connection with the roller 13, but this is not essential to the function of the arrangement.

For explaining the function of the apparatus, it is assumed that a cubic body is to be drawn in perspective. Then, one has first to choose the perspective data, which are commonly given in terms of the D-value and the H-value. The D-value represents the distance over half the angle of sight in the perspective, i. e. the distance from the centre point 29 on the horizontal line 30 to one of the coincidence or ray points 31 or 32, respectively which constructively agree with the turning points of the rollers 13, 14. The H-value represents the height or distance in vertical direction from the midpoint 29 on the horizontal line 30 to the observing point, i. e. the point toward which it is assumed that the centre line of sight is directed when observing the perspective. This point is, in the chosen case, the point 33.

A very usable and illustrative perspective is represented by a D-value of 70 centimeters and an H-value of 52.5 centimeters which will give a perspective angle of 37°, i. e.

$$\tan 37^\circ = 0.75 = 52.5:70$$

This perspective is represented in Fig. 1 of the drawing. The drawn cubic body is assumed to have sides of 12 units of length. One then has to displace and turn the ruler 16 with all locking means open so that the zero point of the scale of the perspective ruler 20 corresponds to the point 33 and to set off along the scale 20 a line of 12 units of length, measured along the perspective scale. Thereby one will obtain the corner point 34. By a similar operation of the scale of the perspective ruler 19 one will obtain the point 35, and finally, one can without any respect to the distances, draw the lines 36 and 37, whereby the base surface of the cubic body is completed.

For constructing the height of the cube one puts the linear ruler 18 so that the zero point of its scale corresponds to the corner point 33, and then the chosen height of 12 units of length are set off along the vertical line, the auxiliary point 42 thus being obtained. In this connection, it is suitable to draw the vertical lines 39 and 40 although one still does not know their length. For this purpose, the locking member 27 is clamped so that the grip 17, the linear scale 18, and the ruler 16 are mutually in fixed positions. An auxiliary mark 41 is drawn, and by elongating or shortening the ruler 16 in correspondence with the auxiliary mark 41 the linear ruler 18 is displaced in parallel to the points 34 and 35, and the two vertical lines 39 and 40 are drawn.

The length of the sides 39 and 40 then should be determined. For this purpose, the locking member 27 is again released, the apparatus is put in such a position that the zero point of the scale

corresponds to point 38, and the locker 28 is clamped so that the length of the ruler 16 is fixed. The ruler then is turned until it corresponds with the auxiliary mark 41, and finally, point 42 is set off on the connection line, corresponding to the zero point of the scale. By means of the scale of the linear ruler 18, the distance between the points 42 and 38 is finally set off in vertical direction from point 33, and the corner point 43 has been obtained. The upper surface of the cube is thereafter drawn, using the rulers 19 and 20, so that the lines 44 and 45 will automatically meet in the ray point 32, the lines 46 and 47 meeting in point 31. The cubic picture is thereafter complete.

It is now obvious that if one, instead of making the side of the cube equal to twelve units of length, had chosen to draw a cube, the side of which was half a unit of length, this cube would have been too small to be drawn with the necessary accuracy. Therefore, one would have had no other choice than to use a reduction factor on the perspective scales of the rulers 19 and 20, thereby using a turnover factor, according to which, for instance, half a unit of length would be replaced by ten units of length, and so on. Thereby, however, the perspective would have been essentially changed, and in order to bring the cube back to the correct perspective, it is therefore of the greatest importance, that one can choose not only the H-value but also the D-value according to every need that may present itself. It is for this reason, that according to the invention the rollers 13 and 14, respectively, are mounted on bars 11 and 12, respectively, which are, in their turn, slidably mounted in relation to the drawing board 10.

As mentioned above, the scales of the perspective rulers 19, 20 are mutually equal but inverted, so that they form the image picture of each other. They are selected for the chosen perspective, i. e. D=70 cm. and H=52.5 cm. When choosing another perspective, one must also use other scales. For this purpose a set of different scales is required, but experience has proved that the needs, most commonly existing in architectural work, advertising, and so on, is suitably met by only four different sets of scales. Suitably, these could be arranged in pairs on each side of the scale bars 19 and 20 so that two scales are placed on their front sides and two scales on their back sides. In this case it is considered sufficient to describe only one pair of scale bars 19, 20.

In many cases it is not necessary to make the perspective drawing in the perfect way, described above, but one may allow for certain approximations. For such cases the triangular template 21 is provided. This corresponds to the direction of the diagonal line of a perspectively reproduced square, the lower left corner of which is assumed to be situated in point 33, that is in the chosen form of executing the connection line between points 33 and 48. Thus it should have been possible to avoid the tedious construction for determining the height of the cube, if, instead of that, one had drawn the line 33-48 by means of the inclined hypotenuse side of the template 21, the ruler 18 first being located in vertical direction. Thereby, it would have been possible to find out the height of the cube in a very simple manner and to complete the cube by drawing the lines 44, 45, 46, and 47. However, it should be observed that the said construction will not be fully exact, if the drawn perspective pictures have large dimensions.

Figs. 2, 3, 4, and 5 show details of the invention, and it is assumed that the function of these figures will be apparent from the above description.

Thus, Fig. 2 shows the grip 17, the parts of the rulers 15, 16, and 18, connected thereto, and the locking members 26 and 27, the latter ones having the form of eccentric plates with a wing, intended to contact the edge 49 of the lower part of the grip under a pressure, that may be controlled by turning the eccentric plates by means of the wing.

Fig. 3 shows a roller 14 from the side, the pivot pin 50, by means of which the roller is guided in the bar 12, and the locking screw 28, by means of which the roller 14 is pressed together in such a way that the ruler 16 which is formed by a transversally bent steel band, cannot move in relation to the roller 14.

Fig. 4 shows the hooks 22, 23 on the ruler 15 for fixing the scale bar 19 in place.

Finally, Fig. 5 shows the fixture 51, which is intended to be fixed on the back side of the drawing board 10 by means of the screws 52, 53, 54, and 55. Two square section pipes or guides 56 and 57, respectively, are secured to the fixture, so that the bars 11 and 12 are movably guided within them. Two lock nuts 58 and 59 are provided for fixing the bars 11 and 12 in correct position. In this way, it is possible in every case to adapt the D-value according to the present need, the usability of the perspective drawing apparatus thereby being increased to a very high degree.

The invention shall not be regarded as limited to the form of execution, shown in the drawing and further described in the above specification but various modifications may be made within the scope of the invention.

What I claim is:

1. Apparatus for producing perspective drawings comprising a drawing board, axially aligned bars slidably mounted on the underside of said board and extending from opposite sides thereof, a roller pivotally mounted on the extending end of each bar, an extensible and retractible tape received on each roller, said tapes being pivotally connected at their point of intersection, non-linear scales calibrated in accordance with the perspective to be drawn detachably secured to said tapes adjacent their point of intersection, a linear scale pivotally secured to said tapes at their point of intersection and extending to one side thereof, a triangular template integral with said linear scale and extending from the opposite sides of the tapes, means for locking said rollers against rotation, and means for locking said tapes and said linear scale against relative pivotal movement whereby a perspective drawing may be accurately constructed to scale.

2. An apparatus as defined in claim 1 in which said tapes are formed of steel and are concave-convex in cross section.

3. An apparatus as defined in claim 1 in which the means for locking said tapes and said linear scale against relative pivotal movement comprise pivotally mounted cams engaging the pivot means pivotally connecting said tapes and said linear scale having finger engaging extensions.

4. An apparatus as defined in claim 1 in which said tapes and said linear scale are pivotally connected by a hand engaging member whereby manipulation of said apparatus is facilitated.

5. Apparatus for producing perspective drawings comprising axially aligned bars adapted to be slidably mounted on the underside of a drawing board and extending from opposite sides thereof, a roller pivotally mounted on the extending end of each bar, an extensible and retractible tape received on each roller, said tapes being pivotally connected at their points of intersection, scales calibrated in accordance with the perspective to be drawn detachably secured to said tapes adjacent their point of intersection, a linear scale pivotally secured to said tapes at their point of intersection and extending to one side thereof, and a triangular template integral with said linear scale and extending from the opposite side of said tapes whereby a perspective drawing may be accurately constructed to scale.

6. Apparatus for producing perspective drawings comprising axially aligned bars adapted to be slidably mounted on the underside of a drawing board and extending from opposite sides thereof, a roller pivotally mounted on the extending end of each bar, an extensible and retractible tape received on each roller, said tapes being pivotally connected at their point of intersection, scales calibrated in accordance with the perspective to be drawn detachably secured to said tapes adjacent their point of intersection, and a linear scale pivotally secured to said tapes at their point of intersection and extending to one side thereof whereby a perspective drawing may be accurately constructed to scale.

7. Apparatus for producing perspective drawings comprising a drawing board, axially aligned bars slidably mounted on the underside of said board and extending from opposite sides thereof, an extensible and retractible tape adjustably secured to the extending end of each bar, said tapes being pivotally connected at their point of intersection, scales calibrated in accordance with the perspective to be drawn detachably secured to said tapes adjacent their point of intersection, and a linear scale pivotally secured to said tapes at their point of intersection and extending to one side thereof whereby a perspective drawing may be accurately constructed to scale.

ERIK G. HYSING.
